United States Patent Office.

JAMES WOOD, OF UTICA, NEW YORK.

Letters Patent No. 82,469, dated September 22, 1868.

IMPROVED WHIFFLE-TREE HOOK.

The Schedule referred to in these Letters Patent and making part of the same.

TO ALL WHOM IT MAY CONCERN:

Be it known that I, JAMES WOOD, of the city of Utica, in the county of Oneida, and State of New York, have invented a new and useful Improved Serpentine Whiffle-Tree Hook; and I do hereby declare that the following is a full, clear, and exact description of the construction and operation of the same, reference being had to the annexed drawings, making a part of the specification, in which—

Figure 1 and Figure 2 are perspective views, showing two different positions which the traces assume while the horses are backing.

A C, in fig. 1, represent the general position which the trace and cock-eye buckle assume in backing.
D is the whiffle-tree, inserted in the hollow body of the ferrule or cap B, forming the base of the hook B'.
A C, in fig. 2, represent the accidental position of the traces and cock-eye buckle in backing of the horse.
B B' represent the peculiar construction of my hook, and the ferrule or cap forming its base, rendering it impossible for the trace to become detached while in the act of backing the horse. The hook is constructed of malleated iron, and a spring in the end is dispensed with.

Claim.

What I claim, and desire to secure by Letters Patent, is—

The cap B, with the hook B' cast or attached to it, both shaped and constructed as herein shown, and secured to the whiffle-tree in the manner and for the purposes herein set forth and described.

JAMES WOOD.
